UNITED STATES PATENT OFFICE.

WILLIAM L. THIEDEMANN, OF MUSKEGON, MICHIGAN, ASSIGNOR TO THIEDEMANN-HARDY COMPANY, OF MUSKEGON, MICHIGAN, A COPARTNERSHIP COMPRISING WILLIAM L. THIEDEMANN AND HAZLETT M. HARDY.

DENTAL OPERATING DEVICE.

Application filed January 9, 1922. Serial No. 527,922.

To all whom it may concern:

Be it known that I, WILLIAM L. THIEDEMANN, a citizen of the United States, residing at Muskegon, in the county of Muskegon and State of Michigan, have invented certain new and useful Improvements in Dental Operating Devices, of which the following is a specification.

This invention relates to dental apparatus but more particularly to operating pieces for use with dental engines and has for its primary object to provide a simple, sanitary and efficient device of this type.

These pieces are used by dentists to operate within the mouth of a patient and the very nature of their use renders them exceedingly unsanitary unless frequently and thoroughly cleaned. Dentists rarely clean more than the outside of these devices because of the time required in the taking apart and the assembly. The piece soon becomes filled with filth and grit which is conducted from mouth to mouth. The grit in this deposit produces a constant grinding of the parts which very materially shortens the life of the device.

I have provided an operating piece which is simple in construction and may be almost instantly taken apart or assembled without the aid of any tools. The disassembled parts may be quickly and easily cleaned, sterilized and oiled in a thorough manner.

The many other objects and advantages of my improved operating piece will be better understood by reference to the following specification when considered in connection with the accompanying drawing illustrating selected embodiments thereof in which:—

Fig. 1 is a central vertical section of an operating piece embodying my invention.

Fig. 2 is an enlarged top plan view of the outer end portion of the piece shown in Fig. 1.

Fig. 3 is an enlarged section on the line 3—3 of Fig. 1.

Figs. 4, 5 and 6 are respectively enlarged transverse sections on the lines 4—4, 5—5, and 6—6 of Fig. 1, and

Fig. 7 is a central vertical section of a portion of a modified form of handpiece.

Referring to the drawing, the operating piece comprises a handpiece 10, a tool holder 11 and a slip joint connection 12. The slip

joint connection is of a well-known type and needs no description as it forms no part of the present invention. The particular type of handpiece illustrated in the drawing has a grip 13 of hard rubber or other suitable substance provided with an axial bore 14 in which operates the spindle 15. This spindle 15 is driven from the usual flexible shafting (not shown) through the medium of the slip joint connection 12. A driving dog 17 is screwed upon the rear end of this spindle to engage a corresponding dog 18 on the connecting shaft 16. Metal ferrules 19 and 20 fit over the front and rear ends respectively of the grip 13 and from bearings for the spindle 15. The slip joint connection 12 slides within the sleeve portion 21 of the ferrule 20 and is adapted to be retained therein by the spring latch 22 engaging a notch in the sleeve. This sleeve is provided with the usual open ended slot 22' to admit the end portion of the latch 22.

A head 23 is formed upon the front end of the ferrule 19 and the tool holder 11 slidably fits over the free end of this head. A spring latch 24 on the tool holder 11 is adapted to engage a laterally projecting pin 25 on the head 23 to securely attach the holder on the head. A pin 26 in the head 23 projects into a slot 27 in the holder 11 to prevent relative rotation. A rotary member 29 operates in the axial bore 28 of the head 23.

The spindle 15 is provided at its front end with a socket 30 which is square in cross section or of a form other than round to receive and fit the correspondingly shaped rear end of the member 29 and form a driving connection between these parts. A head 31 is formed on the front end of the member 29 and this head is provided with a square socket to receive and engage a knob 32 on the inner end of a shaft 33. The knob 32 is square in cross sectional area but the faces are curved longitudinally to provide an angular driving connection between the shaft 33 and the member 29.

A sleeve 34 fits within the bore of the tool holder 10 and forms a bearing for the shaft 33. A star wheel 35 and a collar 36 are secured upon the shaft 33 at opposite ends of the sleeve 34 and act to position the shaft within this sleeve. The outer portion of the tool holder 11 is provided with a transverse

bore 37 within which the tool holding sleeve 38 operates. This sleeve is provided with spaced collars 39 and 40 which fit within the bore and form bearings for the sleeve. 5 The collar 39 forms a shoulder to engage the opposing shoulder 41 produced by the contraction of the bore 37. The bur or other operating tool 42 fits within the sleeve 38 and is prevented from relative rotation therein by the usual contraction 43 at the upper end of the sleeve. A star wheel 44 is formed on the sleeve 38 to mesh with the wheel 35 on the shaft 33 to cause this sleeve to be rotated by the spindle 15. 10 Oppositely disposed guides 45 are formed on the rear face of the holder 11 near its outer end and a tool locking member 46 operates in these guides. This member 44 is preferably made of spring metal and carries a lateral flange 47 which projects over the end of the holder and is adapted to form a closure for the opening 48 in this end wall. The function of this opening 48 is to permit the withdrawal of the sleeve 34 and 15 parts carried thereby. The member 46 forms a closure for the upper end of the bore 37 and is provided with a slot 49 which is adapted to admit and engage the upper end of the tool 42 to lock this tool within the holder. A spring finger 50 on the member 44 presses against the upper face of the holder and provides a frictional resistance to movement of this member in its guides. 20

Assuming that the parts are in their assembled position, as indicated in Fig. 1, the operating piece is disassembled in the following manner:—Insert the finger nail under the flange 47 and draw this flange away from the head as far as the slot 49 will permit. 25 This brings the upper end or head of the tool into registration with the circular enlargement 55 at the end of this slot and permits the tool to be withdrawn from the holder in the usual manner. The member 46 may now be wholly withdrawn from the guides 45. The withdrawal of the member 46 permits the sleeve 38 to be removed by inverting the holder and slightly tapping it if necessary. The sleeve 34 with shaft 33 30 and parts carried thereby may now be removed by depressing the end of the holder and permitting this sleeve to drop through the opening 48. The holder is next detached from the handpiece by lifting the inner end of the latch 24 with the finger nail sufficiently to release this latch from the pin 25 and permit the holder to be withdrawn from the head 23. The detachment of the holder 11 permits the shaft 29 to be removed. 35 The slip joint connection 12 is disengaged by releasing the latch 22 and withdrawing the connection from the sleeve 21. This permits the spindle 15 to be withdrawn from the rear end of the handpiece. The 40 assembly of the operating piece is merely

the converse of the disassembly and equally simple. When completely disassembled in the manner described the parts may be quickly and easily cleaned, sterilized and individually given a coating of lubricating oil. 70

The tool holder hereinbefore described is of the contra-angle type but it should be distinctly understood that my invention is not limited to any particular type. In Fig. 7 is shown a tool holder of the right-angle type. The holder 60 is attached to the handpiece 10 in the same manner as the holder 11. A shaft 61 fits within the socket 30 in the spindle 15 and carries at its outer end a star wheel 62 meshing with the wheel 63 on the sleeve 64. The tool 65 is retained in the holder by a sliding member 66 corresponding to the member 46 in the previous embodiment. No opening is provided in the end of the holder as the shaft 61 may be withdrawn from the head 23 when the tool holder is removed.

It should be clearly understood that the specific embodiments of my invention herein shown and described are for the purpose of illustrating the principles of my invention and I am aware that the form and arrangement of parts would necessarily be very different in different types of operating pieces. I therefore reserve the right to make all such changes therein as fairly fall within the scope of the following claims.

I claim as my invention:

1. A dental operating piece comprising a substantially tubular casing having a bend therein intermediate its ends, a jointed driving spindle extending longitudinally within said casing, a transverse socket formed in said casing near its outer end, a tool holding sleeve revolute within said socket, and means insertible through the outer end of said casing for operatively connecting said spindle and said sleeve. 100

2. A dental operating piece comprising a substantially tubular casing having a bend therein intermediate its ends and provided with an opening at its outer end, a driving spindle extending longitudinally within said casing, a transverse socket in said casing near said outer end, a tool holding sleeve revolute within said socket, means insertible through said opening for operatively connecting said spindle and said sleeve, and a closure for said opening. 110

3. A dental operating piece comprising a substantially tubular casing having a bend therein intermediate its ends and provided with an opening at its outer end, a driving spindle extending longitudinally within said casing, a socket extending transversely through said casing near the outer end, a tool holding sleeve revolute within said socket, means insertible through said opening for operatively connecting said spindle and said sleeve, and a latch adapted to re- 120 125 130

tain said sleeve in said socket and form a closure for said opening.

4. A dental operating piece comprising a handpiece, a driving spindle revolvably 5 mounted in said handpiece, an angle piece slidable over the outer end of said handpiece and provided with a bend intermediate its ends, a transverse socket in said angle piece near the outer end thereof, a revoluble tool 10 holder in said socket, and driving mechanism extending through said angle piece and operatively connecting said spindle with said tool holder.

5. A dental operating piece comprising a 15 handpiece, a driving spindle revolvably mounted in said handpiece, an angle piece slidable over the outer end of said handpiece and provided with a bend intermediate its ends, a latch for attaching said angle 20 piece to said handpiece, a transverse socket in said angle piece near the outer end thereof, a revoluble tool holder in said socket, and shafting in said angle piece 25 operatively connecting said spindle with said tool holder.

6. An angle piece comprising a substantially tubular casing having a bend formed therein intermediate its ends, a transverse socket in said casing near the outer end 30 thereof, a tool holding member revolvable within said socket, and a latch for retaining said member in said socket and a tool in said member.

7. An angle piece comprising a substantially tubular casing, a transverse socket in 35 said casing near the outer end thereof, a tool holding sleeve revolvable within said socket, a latch slidable between guides on said holder to retain said sleeve in said socket and 40 said tool in said sleeve, and means for actuating said sleeve.

8. An angle piece comprising a substantially tubular casing provided with a bend intermediate its ends and having a trans- 45 verse socket near its outer end, a tool operat-

ing sleeve insertible into said socket from the rear end thereof, and a latch for retaining said sleeve in said socket and a tool in said sleeve.

9. An angle piece comprising a substantially tubular casing, a transverse tool 50 socket in the outer portion of said casing, a tool operating sleeve insertible into said socket from the rear end thereof, and a latch plate slidable between guides on said 55 casing into a position to retain said sleeve in said socket and a tool in said sleeve.

10. A dental operating piece comprising a substantially tubular casing, a driving 60 spindle extending longitudinally within said casing, a transverse socket formed in said casing near its outer end, a tool holding sleeve revolvable within said socket, and means insertable through the outer end of 65 said casing for operatively connecting said spindle and said sleeve.

11. A dental operating piece comprising a substantially tubular casing provided with an opening at its outer end, a driving spindle extending longitudinally within said casing, 70 a transverse socket in said casing near said outer end, a tool holding sleeve revolvable within said socket, means insertable through said opening for operatively connecting said spindle and said sleeve, and a closure for 75 said opening.

12. A dental operating piece comprising a substantially tubular casing provided with an opening at its outer end, a driving 80 spindle extending longitudinally within said casing, a socket extending transversely through said casing near the outer end, a tool holding sleeve revolvable within said socket, means insertable through said opening for operatively connecting said spindle 85 and said sleeve, and a latch adapted to retain said sleeve in said socket and form a closure for said opening.

WILLIAM L. THIEDEMANN.
